[57] **ABSTRACT**

A typewriter underline printing control system which adds adding underline starting and completing code signals in the front and the rear of a given character code group to be underlined, respectively. During the printing operation, when the underline starting code is read out, the characters corresponding to the character code are printed successively, while the back-spacing and underline printing operations are automatically repeated each time said character is printed, until the underline completing code is read out.

4 Claims, 3 Drawing Figures

FIG. 1

FIG. 2

FIG. 3

UNDERLINE PRINTING CONTROL SYSTEM FOR USE IN A TYPEWRITER

BRIEF DESCRIPTION OF THE DRAWINGS

FIG. 1 is a system diagram showing an automatic-type typewriter embodying the present invention;

FIG. 2 is a block diagram showing one embodiment of the underline printing control system of the present invention; and

FIG. 3 is a timing chart for the embodiment of FIG. 2.

DETAILED DESCRIPTION OF THE PREFERRED EMBODIMENTS

Referring now to FIG. 1, provided on a keyboard 10 are various types of character keys and function keys.

15 Included among the function keys are forward- and back-spacing keys, a line feed key and an underline key. For a better understanding, only underline key UL is shown separated from the keyboard 10. A control unit 20 serves to control each part of the device.

unit 20 serves to control each part of the device, i.e.,
20 a typewriter. Shown at 30 is a memory and at 40 a printing section. As can be seen from this, when the keys on the keyboard 10 are struck, the code signals corresponding to each key are successively stored via control unit 20 in the memory 30. Thereafter, the code
25 signals stored in the memory are successively read out, decoded and then printed on a recording paper of the printing section 40 as characters corresponding to the aforesaid code signals, under the control of the control unit 20.

30 With the arrangement shown, in case printing of underlines is required, the underline key UL on the keyboard is first depressed, and then the character keys are struck the number of times corresponding to the number of steps requiring underlines, followed by the re-storing of the key UL. According to the aforesaid operation, an underline starting code, a character code group of steps of the number required and an underline completing code are sequentially transmitted.

40 completing code are sequentially stored in the memory. To describe the underline starting and completing codes, they are prepared in the control unit 20 beforehand, and then the underline starting code is selected in response to the setting operation of the UL key, while the underline completing code is selected in response to the resetting operation of the UL key. The

mechanism required for the operations described are well known to those versed in the art, thus the detailed description will be omitted. During the printing operation, code signals stored in the memory 30 are in turn read out at the control unit 20. In this respect, when the control unit interprets that the information read out from the memory 30 is the underline starting code, then the back-spacing instruction as well as the underline instruction for one character will be fed to the

printing section 40, successively and automatically, each time a respective character is printed, until the underline completing code is read out. As a result, the printing section 40 effects the back-spacing operation for one character automatically, each time a respective character is printed, thus inserting or printing underlines under each character printed.

5 There is shown in FIG. 2 the arrangement by which, during the time when the aforesaid underline starting code is read out until the underline completing code is read out, the back-spacing instruction and the underline instruction for one character are automatically issued, each time a character corresponding to each character code is printed.

Turning now to FIG. 2, a flip-flop 11 designates the extent of a passage to be underlined, while a flip-flop 12 designates the underline printing for one character. Shown as block 13 is a counter, in which D-type flip-flops are connected in a multi-stepped manner. FIG. 3 is a timing chart for the system of FIG. 2 and shows the timing sequence of a single back-space and underline operation of the embodiment therein. Cycle periods π_{1-n} are indicated on the horizontal axis, and within each cycle period the sequential timing points T_1-T_4 are shown. The designations T_1-T_4 in FIG. 3 also correspond to the input lines T_1-T_4 shown in FIG. 2. Thus, the input line T_1 in FIG. 2 receives a signal at the timing point T_1 shown in FIG. 3 during each cycle period. Similarly, input lines T_2-T_4 of FIG. 2 each receive signals at their respective timing points T_2-T_4 during each cycle period. FIG. 3 therefore conveys operational system timing information with respect to both cycle periods and timing points within each period.

The reading-out operation of the character code for one character from the memory 30 and the printing operation of the character corresponding to said character code are repeated at a cycle period π . In other words, the content of the memory 30 is read out for each character at the timing T_1 during a cycle period π , and in the case when the aforesaid content is a character code, the printing operation of the corresponding character will be completed within the cycle π . Assume that the code which has been read out at the cycle π_1 and timing T_1 be an underline starting code. Then, the underline starting code will be interpreted at the control unit 20, and thus the underline starting signal is selected. The underline starting signal thus selected will be fed via a gate G_1 to the flip-flop 11 at the timing T_2 , thereby rendering the flip-flop 11 in a set condition. At the timing T_1 of the subsequent cycle π_2 , the first character code requiring underline will be read out, and thus the character corresponding to the aforesaid character will be printed within the cycle π_2 , during which time the setting output from the flip-flop 11 will be fed via a gate G_3 to the flip-flop 12 at the timing T_1 , thereby rendering said flip-flop 12 in a set condition. Likewise, a gate G_4 will be energized at the timing T_4 due to the set condition of the flip-flop 12, such that the counter 13 will advance by one step, issuing the back-spacing instruction. In other words, a "1" signal at the first digit is utilized as a back-spacing instruction signal, which is to be fed to the printing section 40.

When the back-spacing instruction signal is issued from the counter 13, the printing section 40 will effect the back-spacing operation for one character during the subsequent cycle π_3 . Then, the gate G_4 will be again energized during the cycle π_3 at timing T_4 , by a signal on input line T_4 such that the counter 13 will advance by one step, the underline instruction signal will be issued, and the underlining operation will begin, as shown in FIG. 3. In other words, the 1 signal at the second digit of the counter 13 is utilized as an underline instruction signal, which will be fed to the printing section 40. Accordingly, the underline printing of the character printing at the cycle π_2 will be effected at the subsequent cycle π_4 . During the time when the back-spacing or underline instruction signal is being issued from the counter 13, the subsequent information will not be read out from the memory 30. An output signal from the counter 13 is fed via a gate G_5 to the flip-flop 12 at the end of the underlining operation, at the cycle

π_4 and timing T_3 . As a result, the flip-flop 12 will be reset, whereupon the counter 13 will be reset by means of the resetting output from the flip-flop 12. During that time, the flip-flop 11 is maintained in the set condition. Thus, each time a character code is read out from the memory 30, the flip-flop 12 will be set, thus repeating the aforesaid operations.

When the underline completing code is read out from the memory 30 and interpreted at the control section, then the underline completing signal will be issued. This signal will be fed via the gate G_2 to the flip-flop 11 at the timing T_2 , with the result that the flip-flop 11 is restored to the reset condition. Accordingly, the ordinary printing operation free from underline printing will be carried out thereafter.

It will be understood that the above description is merely illustrative of preferred embodiments of the invention. Additional modifications and improvements utilizing the principles of the present invention can be readily anticipated by those skilled in the art from the present disclosure, and such modifications and improvements may fairly be presumed to be within the scope and purview of the invention as defined by the claims that follow.

What is claimed is:

1. An underline printing control system for use in a memory typewriter, comprising:

- a. a memory means for storing a series of character code signals, an underline starting code signal added in the front of said series of character code signals and an underline completing code signal added in the rear of said series of character code signals;
- b. a printing section adapted to successively print the characters corresponding to each character code signal read out from said memory means;
- c. a control unit having a first flip-flop set in response to said underline starting code signal read out from said memory means and reset in response to said underline completing code signal read out from said memory means; and
- d. means within said control unit for feeding to said printing section a back-spacing instruction and an underline instruction for one character, each time the character corresponding to each character code signal read out from the memory means is printed, during the time when said first flip-flop is maintained in a set condition.

2. A system as set forth in claim 1, wherein said means within said control unit comprises a counter adapted to advance successively in response to the setting output from said first flip-flop, each time the printing of one character is completed while said first flip-flop is maintained in a set condition, whereby the outputs from said counter may be successively utilized as a back-spacing instruction signal and an underline instruction signal.

3. A system as set forth in claim 2, wherein said control unit further comprises a second flip-flop set in response to the set output from said first flip-flop and reset in response to a signal from said counter after said underline instructions signal has been generated, said second flip-flop advancing said counter each time the printing of one character is completed so long as said first flip-flop is in set condition, and said second flip-flop resetting said counter in response to the signal

from said counter after said underline instruction signal has been generated.

4. A system as set forth in claim 1, wherein said system further comprises a keyboard provided with an underline key, means, when said underline key is de-

pressed, for selecting the underline starting code signal and means for selecting the underline completing code signal when said underline key is restored to the initial position.
